UNITED STATES PATENT OFFICE

LESTER S. KEILHOLTZ, OF DAYTON, OHIO, ASSIGNOR TO DELCO-LIGHT COMPANY, OF DAYTON, OHIO, A CORPORATION OF OHIO

ELECTRICAL APPARATUS

Application filed November 10, 1926. Serial No. 147,600.

- The present invention relates to electrical systems of control; and particularly to systems in which there is provided a plurality of work circuits energized by a limited source of supply; such as a house lighting plant, which source of supply is sufficient for one of said circuits but insufficient for supplying current to two work circuits simultaneously.
- 10 One of the objects of the present invention is to provide a system of control in which one work circuit is rendered inoperative when another work circuit is rendered operative.
- 15 In certain types of devices which are energized by a limited source of supply, it is desirable that the current for this device be available as soon as there is a demand for current by the device, although another device is receiving current from the source of supply, and although the combined demand is in excess of the current available. Another object of the present invention is to provide a system of control whereby the demand of one of the devices is subordinate to the demand for current by another device so that the superior demand is satisfied and the current supply for the subordinate device is temporarily delayed.
- 25 30 Further objects and advantages of the present invention will be apparent from the following description, reference being had to the accompanying drawings, wherein a preferred form of the present invention is clearly shown.

The figure of the drawing is a diagrammatic view showing a refrigerating system and a water system supplied with current from a generating plant.

- 40 Referring to the drawing, there is shown a pump power head 20 which is driven by a motor 21. Current for the motor is supplied by conductor wires 22 and 23. The power head 20 actuates a pump contained within a well casing 24 and causes water to flow from the well into a pressure storage tank 25 through pipe 26, check valve 27 and a pipe 28. A pressure-operated snap switch 30 is provided with stationary contacts 31 and 32 and with a movable contact 33. The
- movable contact 33 is operated through a rod 34 and lever 35 by a pressure bellows 36 which is connected by pipe 37 with the tank 25.

The refrigerating system comprises a compressor 40 operatively connected with an evaporator 41 and a condenser 42. Refrigerant is withdrawn from the evaporator 41 through pipe 43, and the compressed refrigerant is delivered to the condenser 42 through the pipe 44, whence it flows to the evaporator 41 by the pipe 45. The compressor 40 is driven by an electric motor 47 and said motor is controlled by a pressure-controlled snap switch 48. Switch 48 includes a stationary contact 49 and movable contact 50, which movable contact is operated through a rod 51 and lever 52 by a pressure-responsive bellows 53. Bellows 53 is connected by pipe 54 with the pipe 43, which is a part of the low-pressure side of the refrigerating system.

The source of current herein shown comprises a generator 60 which is driven by an internal-combustion engine 61. The generator and internal-combustion engine comprises a power plant which is of the automatic type, namely, one which is rendered operative automatically when there is a demand for current in a work circuit. For the purpose of this invention it is sufficient to state that the mechanism contained within the box 63 automatically connects a storage battery 64 with the generator 60 for causing said generator to operate as a motor for cranking the engine when there is a demand for current within the work circuit. And, after the internal-combustion engine 61 is rendered self-operative it will drive the generator and supply current to wires 66 and 67. The wire 66 is connected with the movable contact 33 of the snap switch 30 and the wire 67 is connected with the stationary contact 49 of switch 48. The circuit for the motor of the refrigerating system comprises conductors 66, contacts 33 and 32, conductor 68, motor 47, conductor 69, contacts 50 and 49, and conductors 70 and 67. The circuit for the motor 21 of the water system includes conductor 66, contacts 33 and 31, con-

ductor 23, motor 21 and conductors 22 and 67.

When the pressure within the evaporator 41 and pipes 43 attains a certain value 5 which is computed relative to the temperatures desired in the evaporator, the bellows 53 will expand to cause contact 50 to engage contact 49, whereby the circuit is completed between the power plant and the motor 47 10 and, after the power plant is self-operative, current will flow therefrom to the motor 47, whereby the motor drives the compressor 40. When the pressure within the evaporators 41 and 43 attains a certain low value, the bellows 53 will operate to separate contact 50 from contact 49. When the pressure within the storage tank 25 of the water system attains a certain low value, the bellows 36 15 will collapse to cause contact 33 to engage contact 31 to connect the motor 21 with the power plant and after the power plant is self-operative, current from the generator 60 will energize motor 21, whereby water will be forced into the storage tank 25. It 20 will be noted that the demand for current by the refrigerating system is subordinate to the demand for current in the water system. Although the power plant may be supplying current to the refrigerating system, 25 a demand by the water system will cause contact 33 to separate from contact 32 to interrupt the circuit for the motor 47 of the refrigerating system and connect the motor 21 of the water system with the power plant. 30 The current-consuming systems herein shown are merely illustrative and it is to be understood that other types of current-consuming systems or devices may be substituted. Likewise, the generator 60 and 35 engine 61 are herein shown merely for illustrative purposes and any source of current in which the output thereof limited.

From the foregoing description it is apparent that a system of electrical control 40 has been provided for supplying the demands of a plurality of work circuits by a limited source of supply. In the present control system, such devices, in which the flow of current may be delayed temporarily 45 are connected in a work circuit which is subordinate to a work circuit in which current must be supplied substantially as soon as there is demand therefor. Current for the device in the superior work circuit is assured substantially immediately, although current is being supplied to a device in the subordinate circuit. When there is a demand for current by a device in the superior 50 circuit, the device in the subordinate work circuit is disconnected from the source of supply and the current from the source is delivered to the superior circuit. During 55 the interval when there is no demand for current in the superior circuit, current will

be available for devices in the subordinate circuit.

While the form of embodiment of the invention as herein disclosed, constitutes a preferred form, it is to be understood that other forms might be adopted, all coming 70 within the scope of the claims which follow.

What is claimed is as follows:

1. An electrical system comprising a source of supply; a prior demand work circuit energized by said source of supply; a subordinate work circuit energized by said source of supply; a switch responsive to a demand for energy by a work apparatus in the prior demand work circuit; said subordinate circuit including contacts, one of which is directly actuated by said switch when there is a demand for energy by said work apparatus for closing said prior demand work circuit and for directly rendering said subordinate circuit inoperative; and said switch being responsive to the cessation of said demand for directly closing said subordinate circuit and for rendering said prior demand circuit inoperative. 85

2. An electrical system comprising a source of supply; a prior demand work circuit energized by said source of supply; a subordinate work circuit energized by said source of supply; a switch responsive to a demand for energy by a work apparatus in the prior demand work circuit; said subordinate circuit including contacts, one of which is directly actuated by said switch when there is a demand for energy by said work apparatus for closing said prior demand work circuit and for directly rendering said subordinate circuit inoperative; said switch being responsive to the cessation of said demand for directly closing said subordinate circuit and for rendering said prior demand circuit inoperative; and a second switch for rendering said subordinate circuit inoperative. 95

In testimony whereof I hereto affix my 100 signature.

LESTER S. KEILHOLTZ.
